UNITED STATES PATENT OFFICE.

ROBERT SCHOENBERG AND ADOLF MÜLLER, OF ALLENTOWN,
PENNSYLVANIA.

SELF-OPENING UMBRELLA.

SPECIFICATION forming part of Letters Patent No. 686,347, dated November 12, 1901.

Application filed August 7, 1901. Serial No. 71,151. (No model.)

To all whom it may concern:

Be it known that we, ROBERT SCHOENBERG, a citizen of the United States, and ADOLF MÜLLER, a citizen of Germany, and residents 5 of Allentown, Lehigh county, Pennsylvania, have invented certain new and useful Improvements in Umbrellas, of which the following is a specification.

This invention relates to an umbrella which 10 is so constructed that the runner is acted upon by two opposing springs and that it will open or close automatically upon the release of the runner from the retaining-catches.

In the accompanying drawings, Figure 1 is 15 a longitudinal section, partly in side view, of an umbrella-frame embodying our invention. Figs. 2, 3, and 4 are similar views showing the parts in consecutive positions, and Fig. 5 is a detail of the latches that lock the runner in 20 its open and closed position.

The letter *a* represents the tubular stem or hollow stick of an umbrella, which is embraced by the runner *b*, as usual. To the stem *a* are pivoted the ribs that carry the cover 25 and which are connected to the runner by stays, as usual. The runner is provided with a diametrically-extending pin *b'*, which is free to move in a longitudinal slot *a'* of stem *a*.

Within the upper part of stem *a* there is 30 contained a weak closing-spring *c*, extending from the tip of the umbrella to the pin *b'*, against which it bears with its lower end. Within the lower part of the stem *a* there is contained a strong opening-spring *d*, which 35 bears with its upper end against the pin *b'*. The lower end of spring *d* projects into a tubular sleeve *e'* of handle *e*, that telescopes the lower end of stem *a*. This sleeve is longitudinally movable upon the lower portion 40 of stem *a* and is guided thereon by a pin *e'* and slot *a'*. A spring-catch *f* on sleeve *e'*, engaging either one of a pair of perforations *a³* *a⁴* of stem *a*, serves to lock the handle in either of its terminal positions.

45 To one side of tube *a* there is affixed a smaller slotted tube *g*, containing a pair of latches *h* *i*, which are jointly operated by means of a single spring-influenced trigger *j*, to which they are both operatively connected.

50 These latches may be of suitable construction

and are adapted to engage the slot *b²* of runner *b*, so as to lock the umbrella in its open or closed position.

The operation is as follows: To open the umbrella, push handle *e* up to compress 55 spring *d* until the catch *f* falls into upper perforation *a⁴*, Fig. 2. Pull trigger *j* to release the runner from latch *h*, when the spring *d* will force the runner up to open the umbrella and simultaneously compress the weak 60 spring *c*. The umbrella is locked in its open position, Fig. 3, by the engagement of latch *i* with runner *b*. To close the umbrella, depress catch *f* to liberate sleeve *e'* from perforation *a⁴*. The compressed spring *d* will now 65 push the handle down until the catch *f* falls into perforation *a³*, Fig. 4. In this way the tension of spring *d* is taken off runner *b*. By now pulling trigger *f* to release runner *b* from latch *i* the spring *c* will force the runner down to close the umbrella, Fig. 1. 70

It is evident that the invention may be applied to parasols as well as to umbrellas.

What we claim is—

1. An umbrella provided with a tubular 75 stem, a runner, ribs pivoted to the stem, stays that connect the ribs to the runner, an upper and a lower spring engaging the runner from opposite sides, a tubular handle movable upon the stem and engaging the 80 lower spring, means for locking the handle in its terminal positions, and means for locking the runner in its terminal positions, substantially as specified.

2. An umbrella provided with a tubular 85 slotted stem, a runner having a pin movable within the slot, ribs pivoted to the stem, stays that connect the ribs to the runner, an upper weak spring and a lower strong spring within the stem and bearing against opposite 90 sides of the pin, a tubular handle movable upon the stem and adapted to engage the lower spring, means for locking the handle in its terminal positions, and means for locking the runner in its terminal positions, substantially as specified.

3. An umbrella provided with a tubular stem, a runner, ribs pivoted to the stem, stays that connect the ribs to the runner, springs engaging the runner from opposite sides, a 100

tubular handle movable upon the stem and
engaging the lower spring, means for lock-
ing the handle in its terminal positions, a
pair of latches adapted to engage the runner,
5 and a trigger operatively connected to both
of said latches, substantially as specified.

Signed by us at New York city, county and

State of New York, this 6th day of August,
1901.

ROBERT SCHOENBERG.
ADOLF MÜLLER.
